J. G. MACLAREN

POWER CONTROLLER FOR PNEUMATIC DISPATCH SYSTEMS

Filed Dec. 3, 1924

Inventor:

James G. MacLaren.

ATMOSPHERIC PRESSURE

Att'y's

UNITED STATES PATENT OFFICE.

JAMES G. MACLAREN, OF MAMARONECK, NEW YORK, ASSIGNOR TO THE LAMSON COMPANY, OF SYRACUSE, NEW YORK, A CORPORATION OF MASSACHUSETTS.

POWER CONTROLLER FOR PNEUMATIC-DISPATCH SYSTEMS.

Application filed December 3, 1924. Serial No. 753,637.

To all whom it may concern:

- Be it known that I, JAMES G. MACLAREN, a citizen of the United States of America, and resident of Mamaroneck, in the county 5 of Westchester and State of New York, have invented new and useful Improvements in Power Controllers for Pneumatic-Dispatch Systems, of which the following is a specification.
- 10 This invention pertains to pneumatic dispatch systems of the so-called "minimum flow" vacuum type and relates more particularly to automatic power controlling apparatus for use in such a system.
- 15 Power control apparatus of this general character is disclosed in the patent to Libby No. 968,576, dated August 30, 1910. The patented apparatus provides automatic pressure actuated means for initiating a carrier propelling air flow through the transmission tube whenever a carrier is entered therein as well as means for cutting off such flow after the lapse of a predetermined period of time. While I regard the patented 20 device as generally correct in principle and highly effective in practice I believe it preferable to have the cessation of carrier propelling air flow depend directly upon the discharge of the carrier from the delivery 25 end of the tube rather than upon the operation of a timing device, and the principal object of this invention is to devise an improved power control apparatus comprising means actuatable automatically upon insertion of a carrier within the dispatch terminal to initiate flow of the air propelling current and also operating automatically 30 when the last carrier emerges from the delivery terminal to cut off the air current 35 without appreciable delay.

In the accompanying drawings I have disclosed one preferred embodiment of the invention by way of example:—

Fig. 1 being a fragmentary view illustrating a part of the central station desk of a pneumatic system having the improved power control apparatus applied thereto;

Fig. 2 being a vertical section diametrically through the suction tube of the control apparatus, the controlling valve being shown in normal or closed position;

Fig. 3 being a view similar to Fig. 2 but

with the controlling valve open but just on the point of closing;

Fig. 4 being a section substantially on the line 4—4 of Fig. 2;

Fig. 5 being a section on the line 5—5 of Fig 3; and

Fig. 6 being a diagram illustrative of the character of the pressure cycles occurring in control apparatus of the general type to which the present invention relates.

Referring to the drawings, the numeral 1 indicates a fragmentary portion of the central station desk of a pneumatic dispatch system comprising transmission tubes, such for example as the tubes 2, which lead from the central station to remote sending stations and then back to the central station desk. Each tube 2 is furnished with a delivery terminal 3 and is provided with a continuation 4 connecting it to an individual power control device indicated generally by the numeral 5. This power control device is connected in turn by means of a suction tube 7 to a vacuum drum or header 8 in which a low pressure is continually maintained by means of a suitable pump, exhauster or equivalent apparatus, not shown.

An open ended dispatch terminal 6 is provided at the central station for each of the transmission tubes 2, each dispatch terminal forming the entrance to that run of the tube which leads to the corresponding remote sending station. The above arrangement in general is old and well known in this art and further details of such general arrangement are therefore unnecessary, the present invention being confined to improvements in the power control apparatus per se.

Referring particularly to Figs. 2 and 3, the power control apparatus is shown as comprising a hollow casing having an elongate body portion 9 provided with a passage adapted to connect the transmission tube 4 with the suction 7. The upper end of the casing 9 is preferably provided with a flange 10 for the reception of the lower end of the tube 4 while the lower end of the casing is likewise provided with a flange 11 for the reception of the upper end of the tube 7.

For convenience in description the up-

per part 12 of the passage in the body portion 9 of the casing is hereinafter referred to as the "inlet" or "transmission chamber", while the lower part 13 of this passage is referred to as the "suction" or "outlet chamber".

The upper part of the casing 9 is furnished with oppositely directed cylindrical hollow arms 14 and 15 respectively having their axes in substantial alignment and at right angles to the axis of the casing 9. These hollow arms form a guideway for a sliding piston valve comprising the cylindrical shell or valve proper 15^a and the head 16. This piston valve fits snugly within the space 17 in the hollow arm 14 and the head 16 thus forms a movable wall for such space.

The piston valve is also provided with a hollow stem 16^a coaxial with the head 16 and projecting out through the open end of the shell 15^a into the hollow arm 15. At its outer end this sleeve 16^a is furnished with a secondary head 18 having a sliding fit against the inner surface of the arm 15 to assist in guiding the shell 15^a in its movements.

A coiled tension spring 20 is disposed within the hollow stem 16^a and has one end attached to the head 16 of the piston valve by means of a stud 21. The opposite end of the spring is connected to a screw 22 engaging a threaded opening in the cap or head 23 which forms a closure for the outer end of the hollow arm 15. This cap or head 23 is also furnished with a threaded opening for the reception of a stop screw 24 which projects into the interior of the arm 15 and is engageable by the head 18 of the piston valve to limit movement of the latter in one direction under the action of the spring 20.

This stop screw 24 is so set that when the head 18 contacts therewith a small space 45 or crevice 25 is provided between the edge of the valve shell 15^a and the adjacent wall of the casing 9. This crevice provides for the normal minimum flow of air from the inlet to the outlet chamber of the casing 50 which is necessary for the proper operation of control apparatus of this general type. By the provision of the adjustable stop 24 this minimum flow of air past the closed valve may be varied as desired.

The cap 23 closing the hollow arm 15 is also furnished with an opening 26 to admit atmospheric pressure to the space between such cap and the head 18 of the piston valve. In order to prevent the piston valve 60 from rotating within its cylindrical guideway, a rod 19 is disposed longitudinally of the guideway in which the piston valve slides, the latter having openings for the passage of the rod. This rod is secured in

fixed position eccentrically of the guideway 65 and this prevents the valve from rotating.

The space 17 in the hollow arm 14 is connected to the inlet chamber of the casing by means of a passage 27 provided in a suitable boss 27^a on the upper side of the 70 arm. The capacity or cross sectional area of this passage may be varied by means of an adjustable screw 28. For limiting the degree of opening of the piston valve an adjustable stop screw 29 is provided in the 75 outer closed end of the arm 14.

The space 17 communicates with the atmosphere by means of passages 30^a and 30^b in the boss 27^a, these passages merging into 80 a single passage 30 which leads to a valve orifice 31 communicating with the outer atmosphere by means of passages 32 and 33 (see Fig. 3).

The valve orifice 31 is normally closed 85 by means of an auxiliary valve 34 secured to a valve stem 35 carried by a piston 36. This piston slides in a cylindrical casing 37 which may form an integral part of the main casing of the control apparatus, or may as herein shown, be formed as a 90 separate member and connected to the main casing by means of screws 38.

This casing 37 is provided with spaced heads 39 and 40 respectively. The space 41 between the head 39 and the piston 36 is connected by means of a passage 42 with the outlet chamber 13 of the body portion of the casing. The chamber 43 at the opposite side of the piston 36 communicates with the outer atmosphere by means of orifices 44 and 45 in the head 40. The orifice 44 is freely open at all times but is very small, so that the passage of air therethrough is greatly restricted. The orifice 45 is much larger than the orifice 44 and is provided with a check valve 46 which permits free discharge of air from within the casing 37 but which substantially prevents entrance of air through the orifice 45.

A light coiled spring 47 surrounds the valve stem 5, being interposed between the head 39 of the casing and the head 36 of the piston. This spring thus tends to move the piston to the right as illustrated in the drawings and to open the valve 34, thus to permit free entrance of air at atmospheric pressure into the space 17.

In order to obtain a clear understanding of the mode of operation of this device it is desirable to consider the cycles of pressure variation occurring in the inlet and outlet chambers of minimum flow control valves of the general type to which this invention pertains. These cycles are illustrated in a diagrammatic manner in Fig. 6 wherein the ordinates represent suction or vacuum in ounces or inches of water for example while abscissæ indicate time intervals.

In this diagram the solid line is intended to indicate pressure conditions in the transmission or inlet chamber of the casing, while the dotted line indicates pressure conditions in the suction or outlet chamber of the casing.

Assuming that the main valve is closed and that a minimum flow of air is taking place from the inlet chamber to the outlet chamber the suction in the outlet chamber will be but slightly below that of the vacuum drum, as indicated for example at 51 in the diagram. On the other hand, the suction in the inlet chamber will be almost nil due to the restricted character of the passage leading from the suction chamber to the transmission chamber. This inlet chamber suction may be indicated at 50 in the diagram.

When a carrier is introduced into the transmission tube the free entrance of air into the latter is thus obstructed so that the bleeding of air from the tube through the minimum flow passage gradually reduces the pressure in the transmission tube. The point 52 in the diagram is intended to indicate the time at which the carrier is introduced and from this point the suction gradually rises until it reaches some point such as 54 in the diagram.

The insertion of the carrier in the transmission tube and the restriction of the free entrance of air into the latter may also have a slight effect upon the pressure in the suction or outlet end of the casing for the reason that a lesser quantity of air is admitted to this end of the casing through the minimum flow passage. However, as this end of the casing is directly connected to the vacuum drum, the drop in pressure is relatively slight. On the line indicating suction in the outlet end of the casing the point 53 corresponds to the entrance of the carrier into the transmission tube and from this point the vacuum gradually increases to the point 55, substantially as shown.

In the specific embodiment here shown, when the vacuum or suction in the inlet chamber 12 reaches the point indicated at 54 in the diagram, the main controlling valve is opened in opposition to the action of its spring 20 by reason of the differential pressures acting upon the heads 16 and 18 of the valve, the reduced pressure of the inlet chamber being communicated to the space 17 through the passage 27.

Immediately upon opening of the main valve the transmission tube and the suction tube are placed in direct communication so that the suction in the transmission tube tends to rise rapidly, while the suction in the suction end of the casing rapidly falls until these suctions become substantially equal, as indicated on the diagram at the

point 56. The vacuum or suction at this time existing in the casing 9 is somewhat less than that of the suction drum, one reason for this being the fact that the carrier is quite free to move in the tube. The carrier now takes up its flight and during its flight the suction or vacuum in the tube may drop slightly due to the constantly increasing momentum of the carrier, this drop being indicated in the diagram at 57.

When the carrier emerges from the transmission tube the latter is left freely open to the atmosphere so that the vacuum or suction in the tube and casing immediately drops rapidly and approaches atmospheric pressure. However, as the vacuum drum is of a capacity greatly exceeding the capacity of the transmission tube, a certain degree of vacuum is still maintained in the latter, even when it is freely open to the atmosphere, and the vacuum or suction thus maintained while the tube is freely open is greater than that which is necessary to open the controlling valve when the carrier is first introduced and while the main valve is closed. The controlling valve under such circumstances will thus remain open indefinitely unless some other means be provided for varying the pressure conditions in the casing.

In the device herein disclosed the piston 36 is exposed upon its outer face to atmospheric pressure, while its inner face is exposed to the suction obtaining in the chamber 13. When the main valve is closed this suction is sufficient to hold the piston 36 in the position shown in Fig. 2, compressing the light spring 47 and holding the valve 34 closed. Also, after the main valve has opened and during flight of the carrier, although the suction in the chamber 13 decreases to a very considerable extent, it is still sufficient to maintain the valve 36 in this initial position. When the carrier emerges from the transmission tube the suction both in the inlet chamber 12 and in the outlet or chamber 13 of the casing drops very rapidly from the point 58 in the diagram until some point such as 59 is reached at which the spring 47 overcomes atmospheric pressure acting upon the outer side of the piston 36 and opens the valve 34, although at this time the suction in the inlet chamber and space 17 is still sufficient to hold the main valve open.

When the valve 34 opens it permits air at atmospheric pressure freely to enter the space 17 so that the pressure in such space immediately rises and permits the spring 20 to close the main valve. As soon as the main valve begins to close the suction in the chamber 13 begins to rise again, thus tending to pull the piston 36 back to the position shown in Fig. 2. In order to prevent

this piston from closing the valve 34 too quickly and thus cutting off atmospheric pressure from the space 17 before the valve 16 has completely closed, the admission of 5 air into the chamber 43 behind the piston 36 is restricted (by the small capacity of orifice 44) so that the piston 36 moves slowly back to its normal position. The valve 16 is thus closed with certainty and the parts are 10 stored to normal position. As soon as the main valve fully closes, pressure in the inlet chamber returns to that resulting from minimum flow through the casing while the pressure in the suction chamber likewise becomes 15 substantially that of the suction drum.

With the construction thus provided there is no necessity for the provision of any timing arrangement, and the closure of the main valve is dependent wholly upon the delivery 20 of the last carrier from the transmission tube. The structure provided for producing the desired result is of simple character but strong and durable and operates with the utmost certainty under all conditions of 25 use, whether the transmission tube be long or short or whether it be straight or provided with abrupt turns, or long vertical descents.

As herein disclosed the main and auxiliary 30 valves are actuated by pistons but it is contemplated that any other type of pressure operated actuator or "pneumatic" moved by differences in pressure at its opposite sides may be substituted for such pistons. 35 Further, while I have illustrated the invention as embodied in a single specific construction, it is to be understood in general that in its broader aspect the invention is not in any way confined to this particular 40 embodiment, but that various changes and modifications in structural arrangement, proportions of parts and constituent elements employed may be made as occasion 45 may warrant, without departing from the spirit of the appended claims.

I claim:

1. A power control apparatus for a pneumatic dispatch system of the vacuum, minimum flow type having a transmission tube 50 and an exhauster, said apparatus having chambers communicating respectively with the transmission tube and the exhauster, a normally closed valve controlling a passage leading from one of said chambers to the 55 other, a minimum flow from one chamber to the other being permitted when the valve is closed, and means sensitively responsive to pressure change occurring in the chamber communicating with the exhauster to initiate movement of the valve in one direction.

2. A power control apparatus for a pneumatic dispatch system of the vacuum, minimum flow type having a transmission tube 60 and an exhauster, said apparatus having

chambers communicating with the transmission tube and exhauster respectively, a normally closed valve controlling communication between said chambers, a minimum flow of air from one chamber to the other 70 being permitted when the valve is closed, and means for determining movement of said valve comprising elements sensitively responsive respectively to varying conditions in the respective chambers incident to 75 introduction into and discharge of a carrier from the transmission tube.

3. Power control apparatus for a pneumatic dispatch system of the vacuum, minimum flow type having a transmission tube 80 and an exhauster, said apparatus having chambers communicating respectively with said tube and exhauster, a normally closed valve controlling a passage connecting the chambers, a minimum flow of air from one chamber to the other being permitted when the valve is closed, and means for moving the valve comprising pressure operated elements sensitively responsive respectively to pressure fluctuations in the respective chambers. 85

4. A power control apparatus for a pneumatic dispatch system of the vacuum minimum flow type, said apparatus comprising a conduit provided with a normally closed 90 main valve, a minimum flow of air from one side to the other of the closed valve being permitted, the conduit having spaces upon opposite sides respectively of the valve in which the pressure fluctuates differently 100 during a complete cycle of opening and closing of the valve, means for opening the main valve constructed and arranged to initiate its opening upon the occurrence of a predetermined pressure in one of said spaces, and means immediately and directly responsive to the subsequent occurrence of a predetermined pressure in the other of 105 said spaces to initiate closing of the main valve. 110

5. A power control apparatus of the minimum flow vacuum type comprising a conduit provided with a normally closed main valve and a chamber at either side of said valve, a minimum flow of air from one chamber to the other being permitted when the main valve is closed, the air pressure in the respective chambers fluctuating in accordance with different sequences during the operation of the apparatus, means for opening the main valve constructed and arranged to initiate its opening upon the occurrence of a predetermined decrease in pressure in one of said chambers, and means for initiating closure of the main valve upon the subsequent occurrence, during the cycle of pressure fluctuations, of a predetermined increase in pressure in the other of said chambers. 125

6. A power control apparatus of the vac-

uum, open transmission tube type comprising a conduit having a normally closed main valve separating two chambers in which the pressure fluctuates in accordance with different sequences, respectively, a minimum flow of air from one chamber to the other normally being permitted, a pneumatic for opening the main valve upon the occurrence of a predetermined decrease in pressure in one of the chambers while the valve is closed, and means for initiating closing of the valve upon the occurrence of a predetermined pressure increase in the other of said chambers occurring while the valve is open.

7. A power control apparatus for a pneumatic system of the vacuum type having an open ended transmission tube and a suction tube, said apparatus comprising a conduit 20 providing chambers communicating respectively with the transmission and suction tubes, a valve normally separating said chambers, a minimum flow of air from one chamber to the other normally taking place, a pneumatic actuable by the pressure decrease in the transmission tube occasioned by introduction of a carrier for opening the valve, and a second pneumatic directly actuable by increase in pressure in the suction 30 tube incident to delivery of a carrier from the transmission tube to initiate closing of the valve.

8. A power control apparatus for a pneumatic system having a transmission tube and a suction tube comprising a casing having chambers connected respectively with the transmission and suction tubes, a valve normally closing a passage between the chambers, a minimum flow of air normally 40 being permitted from the transmission to the suction tube, means operating upon the occurrence of a drop in pressure in the transmission tube incident to introduction of a carrier therein to open the valve and to maintain it open during the flight of the carrier, and a pneumatic actuable by increase in pressure in the suction tube incident to delivery of the carrier from the transmission tube to render the valve opening means inoperative.

9. Power control apparatus having a transmission tube and an exhauster, said apparatus comprising a conduit providing chambers communicating respectively with the tube and exhauster, a valve controlling a passage connecting said chambers, a pneumatic actuated by pressure change in the first of said chambers for initiating movement of the valve in one direction, and a second pneumatic subject to pressure change in the other of said chambers, to initiate movement of the valve in the opposite direction.

10. Power control apparatus for a pneumatic dispatch system of the vacuum, mini-

mum flow type, comprising a casing having two chambers therein, a main valve controlling a passage connecting said chambers, a pneumatic for moving the valve in one direction upon drop in pressure in one of said chambers, a normally closed auxiliary valve for admitting air at atmospheric pressure to act on one side of said pneumatic to cause the valve to move in the opposite direction, and a second pneumatic, responsive to pressure increase in the other of said chambers, for opening the auxiliary valve.

11. Power control apparatus for a pneumatic dispatch system of the vacuum, minimum flow type, having a transmission tube and a conduit connecting said tube with an exhauster, said conduit comprising two chambers, a main valve controlling a passage connecting said chambers, means tending to close the valve, a pneumatic operable upon drop in pressure in one of said chambers to open the valve, a normally closed auxiliary valve for admitting air to a space at one side of said pneumatic, and an auxiliary pneumatic sensitive to rise in pressure in the other chamber to determine opening of the auxiliary valve.

12. Power control apparatus comprising a casing, a main valve controlling communication between two chambers within the casing, a spring tending to close the main valve, a pneumatic connected to the valve, said pneumatic opening the valve upon decrease in pressure in one of said chambers, a normally closed auxiliary valve for admitting air at atmospheric pressure to a space at one side of said pneumatic, a second pneumatic, subject to low pressure normally prevailing in the other chamber, normally holding the auxiliary valve closed, and a spring 100 tending to open the auxiliary valve.

13. Power control apparatus for a pneumatic transmission tube comprising a casing having a pair of chambers therein, a main valve controlling a passage connecting said chambers, means tending to keep the valve closed, a minimum flow of air past the closed valve being permitted, a piston connected to the valve, said piston being subject to the pressure prevailing in one of said chambers and becoming operative to open the valve when said pressure drops to a predetermined degree, an auxiliary valve for admitting atmospheric pressure to act on one side of said piston, a spring tending to open said auxiliary valve, and a pressure operated element subject to low pressure normally prevailing in the other of said chambers and normally holding the auxiliary valve closed 110 in opposition to its spring.

14. Power control apparatus for a pneumatic transmission tube comprising a casing having an elongate hollow body portion provided at one end with means for connecting it to the transmission tube and at its other 120 130

- 6 end communicating with a source of low pressure, a piston valve guided for movement transversely of the casing and controlling the passage of air through the latter, 5 and means tending to hold the valve closed, the valve having a head subject to pressure conditions obtaining in the transmission tube, drop in pressure in said tube causing the valve to open.
- 10 15. Power control apparatus for a pneumatic transmission tube comprising an elongate hollow casing communicating at one end with the transmission tube and at the other with a source of low pressure, a piston valve sliding transversely of the casing, a spring tending to close the valve whereby to obstruct the passage of air through the casing, a hollow arm projecting from the casing providing a chamber, the head of the 15 valve constituting a movable wall for said chamber, a passage connecting the chamber with the transmission tube end of the casing, and a normally closed passage connecting said chamber with the outer air.
- 20 25. Power control apparatus for a pneumatic transmission tube comprising an elongate hollow casing connected at one end with the transmission tube and at its other end with a suction tube, oppositely extending hollow arms projecting from the casing, a piston valve slidably guided within said arms, means tending to move the valve to a position to obstruct the flow of air through the casing, means normally establishing the 25 transmission tube pressure in one of said arms to act upon the head of the piston valve, a normally closed auxiliary valve for admitting atmospheric pressure to the interior of said arm, and means controlled by 30 the pressure obtaining in the suction tube for determining opening of said auxiliary valve.
- 15 40. 17. Power control apparatus comprising a casing having an elongate portion connected at its opposite ends to a transmission tube and a suction tube respectively, the casing also having a lateral chamber communicating with the transmission tube, a piston having a head forming a movable wall for said 45 chamber, the body of the piston constituting a valve, means tending to move the piston to a position to obstruct the flow of air longitudinally through the casing, a normally closed auxiliary valve for admitting atmospheric pressure to the lateral 50 chamber, a spring tending to open the auxiliary valve, and a piston connected to the auxiliary valve, the head of said piston being exposed on one side to the pressure obtaining in the suction tube.
- 55 60. 18. Power control apparatus for a pneumatic transmission tube comprising a hollow casing communicating at one end with the transmission tube and at its other end with a suction tube, a piston valve sliding
- transversely of the casing, means tending to close the valve to cut off air flow through the casing, and an adjustable stop to limit closure of the valve.
19. Power control apparatus for a pneumatic dispatch system of the vacuum having an open ended transmission tube, said apparatus comprising a main valve, means tending to close the valve whereby to obstruct passage of air through the tube, and an adjustable stop preventing complete closure of the valve whereby to provide for a normal minimum flow of air through the tube, means for opening the valve, and an adjustable stop to limit the degree of opening of the valve.
20. Power control apparatus for a pneumatic dispatch system having a transmission tube, said apparatus comprising a casing connected to the transmission tube, a piston valve slideable transversely of the casing, means tending to close said valve whereby completely to cut off flow of air through the casing and tube, and a stop engageable with the valve to prevent it from closing completely.
21. Power control apparatus for a pneumatic dispatch system having a transmission tube, said apparatus comprising a casing having a passage forming an extension of the tube, the casing being provided with a cylindrical guideway extending transversely of the passage, a piston valve sliding in the guideway, and a fixed rod extending longitudinally of the guideway eccentrically of the axis of the latter, the piston valve having sliding engagement with the rod whereby the latter prevents rotation of the piston valve relatively to its guideway.
22. Power control apparatus for a pneumatic dispatch system having a transmission tube, said apparatus comprising a reciprocal piston valve for controlling air flow through the tube, said valve having a cylindrical shell provided with a head at one end and open at the other, a hollow axially disposed stem united to the head and projecting out through the open end of the shell, and a second head member secured to the outer end of the stem.
23. Power control apparatus for a pneumatic dispatch system having a transmission tube, said apparatus comprising a conduit forming a continuation of the tube, a main valve normally obstructing said conduit and dividing it into inlet and outlet chambers, a pneumatic for opening the valve, said pneumatic being normally subject to the pressure obtaining in the inlet chamber, an auxiliary valve for controlling the admission of air at atmospheric pressure to act on said pneumatic, a second pneumatic exposed upon one side to the pressure obtaining in the outlet chamber, a spring acting in opposition to said last pneumatic

and tending to open the auxiliary valve, and means for retarding the closing of the auxiliary valve.

24. Power control apparatus for a pneumatic dispatch system, of the vacuum minimum flow type said apparatus comprising a main valve for controlling the flow of air through a portion of the system, a pneumatic for moving the valve, means for admitting air to operate said pneumatic, said means comprising a normally closed auxiliary valve, a spring tending to open the auxiliary valve, a piston connected to the valve, and a closed cylinder in which the piston slides, said cylinder having an inlet passage of restricted capacity in its head.
25. Power control apparatus for a pneumatic dispatch system, said apparatus comprising a main valve for controlling the flow of air through a portion of the system, a pneumatic for moving the valve, means for admitting atmospheric pressure to act on said pneumatic comprising a normally closed auxiliary valve, a piston connected to said valve, a closed cylinder in which the piston slides, one head of the cylinder being provided with a small inlet passage and a relatively large outlet passage, and a check valve preventing entrance of air through the outlet passage.

26. Power control apparatus for a pneumatic dispatch system comprising a casing having an inlet chamber and an outlet chamber, a valve controlling flow of air from one of said chambers to the other, a pressure

operated element for moving the valve, one face of said element forming a movable wall for a space connected by a passage with the inlet chamber, said casing having another passage leading from said space to the atmosphere, an auxiliary valve normally closing the latter passage, a secondary pressure controlled element forming a movable wall for a space communicating with the outlet chamber of the casing, and means connecting said latter pressure controlled element with the auxiliary valve.

27. Power control apparatus for a pneumatic dispatch system comprising a casing having an inlet chamber and an outlet chamber, a valve controlling communication between said chambers, a piston for moving the valve, said piston constituting a movable wall for a space within the casing, said space being connected by a passage with the inlet chamber, adjustable means for restricting the capacity of said passage, a second passage connecting said space with the atmosphere, an auxiliary valve normally closing the entrance to said latter passage, a spring tending to open said auxiliary valve, a piston sliding in a cylindrical chamber in the casing, said chamber being connected by a passage with the outlet chamber of the casing, and means connecting the piston with the auxiliary valve.

Signed by me at Pittsburgh, Allegheny Co., Penna., this 31st day of October, 1924.

JAMES G. MACLAREN
